UNITED STATES PATENT OFFICE.

WILLIAM WADE, OF CHICAGO, ILLINOIS.

CREASING AND HEMMING MACHINE.

Application filed July 6, 1925. Serial No. 41,499.

To all whom it may concern:

Be it known that I, WILLIAM WADE, a citizen of the United States, and a resident of Chicago, in the county of Cook and State 5 of Illinois, have invented certain new and useful Improvements in Creasing and Hemming Machines, of which the following is a description; reference being had to the accompanying drawings, which form a part of 10 my specification.

My invention relates to a machine for creasing and hemming fabric and more especially the fabric or material employed for window shades, preparatory to receiving 15 the usual stick or slat at the free or cord receiving end of the shade.

My invention has for its object the provision of a machine whereby the fabric or shades may be provided with a uniform 20 and standard sized hem which may be more quickly produced than has heretofore been the case with the method or practice of forming hems manually; and as a result of my invention, the frequent soiling of the 25 fabric or shade material by the hands of the operator is prevented and considerable time and labor saved.

The objects and advantages of my invention will all be more fully comprehended 30 from the detailed description of the accompanying drawings, wherein:

Figure 1 is a perspective view of my improved machine, with a portion of the bed plate or table broken away.

Figure 2 illustrates, in perspective, a portion 35 of fabric or shade, showing the type of the hem produced.

Figure 3 is a detail perspective view taken 40 on the line 3—3 of Figure 1 looking in the direction of the arrows.

Figure 4 is a detail perspective view taken 45 on the line 4—4 of Figure 1 looking in the direction of the arrows.

Figure 5 is a detail perspective view of 50 the crease and hem forming portion of the machine; illustrating the initial step or action.

Figure 6 is a similar view showing the 55 second stage or step in the crease forming operation.

Figure 7 is a similar perspective view illustrating the third or final stage of the 60 crease forming operation and the position

of the creasing and hem producing mechanism.

In the particular exemplification of the invention as illustrated in the drawings, it comprises a suitable table 10 of width and length sufficient to receive the sheets of fabric or window shades which it is intended to crease and hem; the construction illustrated being more particularly adapted for the creasing and hemming of window shades which are previously cut to size and of predetermined width.

In operation, the shade material, which is usually rolled, is placed on the table and in order to prevent the rolls of material from falling off the table, (where the latter is not in contact at the rear side with a wall or partition), I have shown the table or bed plate 10 provided with an upstanding ledge 11 along what may be termed the rear side, namely the side opposite to that at which the operator is located. The composite 70 table or top 10, which is supported by any suitable framework or standards as at 12, comprises, in addition to the main part or rear section 13, a metallic strip 13^a stationarily mounted; a metallic strip or section 14 of suitable width and yieldingly mounted on the cross-members 12^a so as to permit a transversely shifting thereof, as is also true with the section or metallic strip 15 which may be of any desired width and which constitutes a portion of the creasing mechanism; while the side or portion of the table or top 10 adjacent to the operator comprises an immovable section or board 16 suitably supported and secured to the top cross members of the supporting frame or standard. The sections 13^a, 14 and 15 are preferably 80 metal plates or bars.

The lower portion of the supporting frame or standard is shown provided with 95 a tie rod at 17 which also provides a fulcrum for the arms 18, 18, of the foot-lever or treadle 19. The lever at the forward or operating side of the machine rests on a cross-bar 20 which extends lengthwise of 100 the table and is adapted to be reciprocated vertically in the guideways formed by the members 21 secured to the supporting frame of the machine. The ends of the cross-bar 20 are provided with rods 22, 22, disposed 105 upwardly through suitable openings in the

plate or section 14. The upper ends of the rods are provided with a cross-strip or member 23 which may be held in place in any suitable manner, as for example by the nuts 24 secured on the upper threaded end of the rods 22. The sides of the cross-strip or member 23 are shown provided with the plates 25, 25 secured to the block or strip 23 in any suitable manner so as to have the lower longitudinal edges of the plates 25 depend beneath the strip 23 which latter is substantially of the same or slightly greater width than the width of the strip or table section 14, so that the depending longitudinal edges of the plates 25, 25 may enter the slots 26, 26 on opposite sides of the strip or table section 14 when the foot-treadle or pedal 19 is depressed, which in turn depresses cross-bar 20 thereby moving the composite fabric or shade controlling element, composed of the block 23 and plates 25, downwardly through the medium of rods 22. As is apparent from the construction shown, if the fabric or window shade is brought beneath the vertically reciprocating element, downward movement of the element will cause the fabric, or window shade indicated at A, to be forced down into the slots 26 as shown in Figure 5. The strip or table section 14 is yieldingly held in normal position relative to the permanently fixed portion 13^a by means of one or more springs as shown at 27, see Figure 3; the cross-bar 20 with the connecting rods 22 having sufficient play to permit the slight lateral movement of the various elements referred to.

The strip or section 15 is shown provided with a pin or lug 28 (see Figure 3) to which one end of a spring 29 is secured, while the other end of the spring is secured to an immovable portion of the table or supporting frame. A similar arrangement or spring is preferably employed at each end of the strip 15; and these springs tend to return the strip to normal position, namely in spaced relation with the strip 14.

The supporting frame or standard, beneath the table top, is provided with suitable brackets as at 30, in Figure 1, to support a rocker shaft or rod 31 which, at a convenient point, is provided with an operating lever or handle 32 fixedly secured to the rod or shaft 31 so as to rock the latter when the lever 32 is oscillated upwardly.

The rod or shaft 31 is also provided with arms 33 fixedly secured thereto; with the upper ends of the arms 33 engaging with the strip 15 so as to cause the latter to move toward strip 14 when rod or shaft 31 is rocked on its axis by the upward movement of lever 32; the strip 15, together with rocker shaft 31 and the hand lever 32, being returned to normal position through the action of the spring or springs 29. It is apparent

that sufficient movement of lever 32 will not only move strip or jaw member 15 into juxtaposition with strip 14, but will also cause strip 14 to be shifted toward the immovable portion 13^a of the table and thus close the gaps or slots 26 on opposite sides of strip 14 and as a result definitely crease the material or window shade which has previously been inserted into the slots through the action of the reciprocating composite crease forming head previously described.

In order that the fabric or window shade may be held in place when the crease forming plates 25, 25 of the composite crease forming head come in contact with the fabric or shade, the composite head is shown as also involving a flat strip or plate 34 which extends full length of the cross strip or member 23 and is yieldingly supported therebeneath by means of the bolts or pins 35 which extend through suitable openings in the cross strip or member 23; the pins or bolts 35 being surrounded each by a coil spring 36, one end whereof presses on the plate 34 while the other end is seated in the countersunk opening 37 in the cross strip or member 23, thus yieldingly maintaining the plate 34 in spaced relation with the cross strip 23. The length of the pins 35 are preferably such that the plate 34, when in normal position, will be slightly above the lower edges of the pair of plates 25. As is evident from the constructions shown in Figures 5 and 6, the plate 34 will press the fabric or window shade material onto the strip 14 and maintain its position while the creaser head is further depressed (which is permitted by the compression of the coil springs 36) so as to permit the plates 25, 25 to force the material sufficiently into the slots 26 in order to provide a proper crease in the material.

In operation, the operator places the rolled end of the window shade on the permanent portion 13 of the table and brings the free end of the shade beneath the composite creaser head a distance sufficient to permit of the formation of a suitable hem; he then depresses foot lever 19 so as to bring the composite creaser head into contact with the material, causing plate 34 to hold the material firmly on strip 14 while the plates 25 place the material into the slot 26. With the material in this position, as shown in Figure 5, the operator then grasps lever 32 and moves same upwardly so as to rock rocker shaft 31 which causes the arm 33 thereof to force table section or strip 15 toward strip 14. The initial upward movement of lever 32, however, is just sufficient to frictionally hold the material by the strips 15, 14 and the permanent portion 13^a of the table, but not sufficient to grip the plates 25, 25 of the composite creaser head which

latter is allowed to move upwardly back to normal position resulting from the operator taking his foot off the foot treadle 19; the initial gripping of the fabric by the 5 movement of the strips 15 and 14 being shown in Figure 6, while the final creasing operation of the material, namely after the composite creaser head has been released being shown in Figure 7. Upon releasing 10 the foot treadle 19, the composite creaser head returns upwardly through the action of the springs 38; one end being secured to the cross-bar 20 while the other end is secured at a suitable stationary point on the 15 supporting frame, at which time the operator applies greater upward pressure on hand lever 32, causing strip 15 of the table top to grip the material between strip 15 and strip 14 while the latter has simultaneously been moved into juxtaposition with the permanent table portion 13^a so that a pair of heavy or very defined creases are formed in the material or window shade, with the result that when the hand lever 32 is released 20 and the strips 14 and 15 returned to normal separated position, the window shade material will automatically fold over into the condition shown in Figure 2 and thus provide the desired hem wherein the free 25 end *a* of the material folds over onto the portion *b* and the latter, with the infolded portion *a*, in turn folds over onto the main portion of the fabric or window shade A. The hem is then stitched in place at the 30 juncture of the operations *a* and *b* and the window shade is then ready to receive the usual strip or slat for the cord-receiving end of the window shade.

In order that hems of different widths 40 may be made, I provide a gauge or control mechanism shown in the particular exemplification in the form of the threaded pins or bolts 39 secured to the cross-bar 20 and passing upwardly through apertured angle members 40 which are secured to the standards or uprights 12. The pins or bolts 39 are of comparative length and are provided with one or more nuts 41 which may screw lengthwise of the pins and are adapted to engage the stop block or angle 45 50 55 60 65 70 75 80 85 90 95 100 105 110 115 120 125 130 members 40 and thereby limit the downward movement of cross-bar 20 and hence the downward stroke of the composite head carrying the plates 25, 25.

If the shade or material is to be provided with a comparatively narrow hem, the nuts 41 are screwed down on the pins 39 to the desired extent, thereby limiting the degree of insertion of blades 25 into the slots 26 and hence controlling the amount of material depressed into the slots 26. As the actual creasing of the material takes place at the point immediately beneath the plates 25, it is apparent the width of material between the two defined creases will be increased as

the blades are allowed to further pass downwardly between the movable table sections; in other words, a wider hem is produced when the blades pass downward to a greater extent than shown in Figure 5 for example. 70

It will be understood that when the nuts 41 are screwed to the upper end of the pins 39 the cross bar 20 with the creaser head will then be permitted to move so as to provide a hem of maximum width; while adjustments of the nuts to a point intermediate of the upper end of the pins and the cross bar will provide hems of narrower width. 75

In order that the movable sections 14 and 15 may not be displaced or have longitudinal movement, I provide these sections on the lower surfaces thereof with transversely disposed blocks or strips 42 at adjacent opposite ends of the sections and disposed to what may be termed the outer sides of the cross members or bars 12^a, with the blocks or strips 42 engaging with the cross members 12^a while permitting free sliding movement of the sections 14 and 15 on the cross members 12^a. 80 85 90 95 100 105 110 115 120 125 130

In order that the cross head with its plates 25, 25 may move downwardly on opposite sides of the section 14, the plate 25 on what may be termed the rear side of the cross head, namely the side disposed toward the table portion 13, is provided with cut out portions as shown at 43 at points adapted to register with the springs 27, in order that the plates 25 will not interfere with the springs 27; and the front stationary section or board 16 of the table top on the lower side is provided with cut out portions or grooves to receive the upper ends of the arms 33 which engage with the edge of the metallic plate or section 15.

My improved machine is adapted to provide the window shade or material with either a single hem as shown in Figure 2 or with what may be called a duplex hem where the material is folded once more upon itself, but in the opposite direction, this type of hem being provided by turning the material or window shade over and creasing it in the opposite direction. With my improved machine, it is apparent that a hem disposed at right angles to the sides of the shade will at all times be formed regardless of whether or not the free end of the window shade is cut true, as the creasing and hemming operation is usually formed with the window shade rolled up with the exception of the free or slat receiving end which is to be provided with the hem. The shade being rolled up in the manner stated, may be placed by the operator against the rear side of the creaser head so as to be aligned therewith (the window shade being rolled up properly) thus inducing the hem to be properly disposed, namely at right angles to the sides of the shade. As the material is forced

- into the slots 26, it is evident that when the movable sections are brought into juxtaposition and into close relation with the non-movable section 13^a, that the window shade 5 will be given a very defined crease which will induce the material or window shade to fold upon itself and thus automatically provide the hem and therefore obviate the necessity for manually folding the material over, 10 which operation is at present in use and results in serious injuries to the hands of the operator because of the constant frictional contact with the shade material in producing a definite crease and hem.
- 15 I have shown what I believe to be a simple adaptation of my invention, which has been described in terms employed merely as terms of description and not as terms of limitation, as modifications are possible and may 20 be made without, however, departing from the spirit of my invention.
- What I claim is:
1. A creasing and hemming machine, comprising a plurality of parallelly arranged 25 crease forming members adapted to move toward each other, means whereby the material to be creased and hemmed is forced between said members, and means whereby said members are moved into crease forming 30 relation.
  2. A creasing and hemming machine, comprising a work holding table, a plurality of crease forming members arranged parallel with and in the plane of the table- 35 top, means whereby the material to be creased and hemmed is forced between said members, and means whereby said members are moved into crease forming relation.
  3. A creasing and hemming machine, 40 provided with a flat work holding top composed of longitudinal parallel sections normally held in spaced relation, certain of said sections being movable toward each other, means whereby the movable sections may be controlled, and means whereby the material to be creased is forced between said spaced 45 sections and the width of the hem thereby controlled.
  4. A creasing and hemming machine, 50 comprising a work holding top composed of stationary and movable sections, the movable sections being adapted to slide transversely toward the stationary section, means for yieldingly maintaining the movable sections in spaced relation with the stationary 55 section and with each other, means for moving the sections toward each other and toward the stationary section, and means for forcing the material to be creased between 60 the respective sections.
  5. A creasing and hemming machine, 65 comprising a stationary section, a pair of transversely movable sections arranged flush with the stationary section, a lever operably connected to one of said pair of movable sec-

tions whereby the latter are forced toward each other and toward the stationary section, springs for normally holding the sections in spaced relation, a head reciprocatingly mounted above the sections and provided with material engaging longitudinal edges adapted to force the material between the sections, and means for reciprocating the head.

6. In a creasing and hemming machine, a work holding table composed of longitudinal sections normally arranged in spaced relation so as to provide material receiving slots, certain of said sections being movable toward each other so as to crease the material therebetween, means for forcing the material into said slots composed of spaced vertically arranged plates, a yieldingly held presser plate intermediate of the vertically arranged plates whereby the material is held on one of said movable sections, the vertically arranged plates and presser plate being mounted to move as a unit toward and away from the movable sections, means whereby the movable sections are controlled, and means whereby the first mentioned means are controlled.

7. A creasing and hemming machine, comprising a work holding table having stationary and movable sections, the movable sections being normally held in spaced relation with each other and with the stationary section whereby material receiving slots are provided lengthwise of the table, a reciprocating head disposed above one of the movable sections and provided with material engaging members laterally spaced apart a distance slightly greater than the width of said movable top section for forcing the material downward on opposite sides of said movable section, a pressure applying plate yieldingly mounted intermediate of the members of said head whereby the material is held in firm relation with said movable section, means for moving said head downwardly into contact with said material, and means whereby the movable sections are forced toward each other and toward the stationary section.

8. A creasing and hemming machine, comprising a work holding table, a plurality of crease forming members arranged parallel with and in the plane of the table top, means for normally maintaining said crease forming members in spaced relation, means whereby the material to be creased and hemmed is forced between said members, means for determining the extent of operation of said second mentioned means, and means whereby said members are moved into crease forming relation.

9. A creasing and hemming machine, comprising a work holding top composed of stationary and movable sections, the movable sections being adapted to slide transversely

toward each other and toward the stationary section, means for preventing longitudinal movement of said movable sections, means for yieldingly maintaining the movable sections in spaced relation with each other and with the stationary section, means for moving the movable sections toward each other and toward the stationary section, material

controlling means reciprocable above said sections for forcing the material to be increased between the respective sections, regulable means whereby the extent of reciprocation of said last mentioned means may be controlled, and means whereby said reciprocable means is operated.

WILLIAM WADE.
